INVENTOR
Harry E. Campbell
BY Park Benjamin
his ATTORNEY

UNITED STATES PATENT OFFICE.

HARRY E. CAMPBELL, OF NEW YORK, N. Y.

METAL WINDOW-FRAME.

1,252,087.

Specification of Letters Patent. Patented Jan. 1, 1918.

Original application filed November 13, 1916, Serial No. 131,060. Divided and this application filed July 13, 1917. Serial No. 180,262.

To all whom it may concern:

Be it known that I, HARRY E. CAMPBELL, a citizen of the United States, residing at New York, in the county of New York and 5 State of New York, have invented a certain new and useful Improvement in Metal Window-Frames, of which the following is a specification.

The invention relates to metal window-10 frames, and consists in the construction set forth, whereby moisture entering the hollow jambs is drained to a concavity on the front side of the sill.

This application is a division of my application Serial No. 131,060, filed November 13, 1916.

In the accompanying drawings—

Figure 1 is a vertical section of a window-frame containing my invention. Fig. 2 is a 20 similar section of the lower portion of the frame and sill on the line 2, 2 of Fig. 4. Fig. 3 is a front elevation of one side of the frame, with parts broken away and end section on the line 3, 3 of Fig. 1. Fig. 4 is 25 a horizontal section on the line 4, 4 of Fig. 1.

Similar numbers and letters of reference indicate like parts.

The frame members comprise a metal sill A, two hollow jambs B, C resting thereon, 30 and a box lintel D on said jambs. In the inner wall of each jamb are two parallel vertical slots E, F. On the vertical side rails of each of the sashes G, H are laterally projecting metal plates I, J, which pass through 35 said jamb openings. To said plates are secured extension plates K, L which extend to the outer wall 8 of the jamb. As here shown, the two sashes G, H counterbalance 40 one another, the connecting chains (one of which is shown at M) passing over pulleys N journaled within the lintel D.

The sill A has a horizontal upper wall 34, on which is an upwardly extending flange or dam 35. Integral with said upper wall 45 are vertical pockets 38 which extend through said wall, as shown in section in Fig. 3. In front of the flange there is a concavity 35*, Fig. 4, in the sill, and at each end of said concavity is a wall 36. The bottom 37 of 50 the concavity is outwardly and downwardly inclined. Said pockets 38 open through the end walls 36, and register with the lower end of one of the vertical slots formed in the

inner walls of the jambs. Hence any moisture accumulating in the jambs is drained 55 into the pockets 38, and thence escapes to the inclined bottom 37 of the concavity, and so over the outer edge thereof. The pockets receive the lower ends of plates J, L. A plate 39 on the bottom rail of the lower 60 sash, when said sash is in closed position, forms a joint with the flange 35.

From the foregoing it will be seen that I here provide for draining moisture accumulated in the jambs to the inclined sill 65 bottom.

I claim:

1. A metal window-frame, comprising hollow jambs and a sill formed with end walls and a concavity on its front side extending 70 longitudinally between said walls, the said end walls having vertical openings communicating with the space inclosed by said jambs, whereby moisture accumulated in said jambs is drained into said concavity. 75

2. A metal window-frame, comprising hollow jambs, a sill, an upwardly extending longitudinal flange on said sill, and, in front of said flange and adjacent thereto, end walls, and a concavity extending longitudinally between said walls and having a downwardly and outwardly inclined bottom, the said end walls having vertical openings immediately in front of said flange and communicating with the space inclosed 85 by said jambs, whereby moisture accumulated in said jambs is drained into said concavity. 80

3. A metal window-frame, comprising hollow jambs, each jamb having in its inner wall a vertical longitudinal slot, a sill formed on its front side with end walls and a concavity extending longitudinally between said walls, the said end walls having vertical openings into said concavity registering with the lower ends of said jamb slots, whereby moisture accumulated in said jambs is drained into said concavity. 95

4. A metal window-frame, comprising hollow jambs, a sill comprising a horizontal upper wall having integrally formed transverse pockets extending below said upper wall, end walls, and a concavity on the front side of said sill extending longitudinally between said end walls, the said pockets opening through said end walls and into said 100 105

concavity, whereby moisture accumulating in said jambs is drained into said pockets and from said pockets into said concavity.

5. A metal window-frame, as in claim 4,
the said jambs having vertical guide slots
in their inner walls registering with said
pockets.

In testimony whereof I have affixed my
signature in presence of two witnesses.

HARRY E. CAMPBELL.
